TELEPHONE SYSTEM

Bernard Anthony Hensler, London, England, assignor to Siemens Brothers & Company Limited, London, England

Application March 11, 1937, Serial No. 130,388
In Great Britain March 16, 1936

26 Claims. (Cl. 179—27)

The present invention relates to telephone systems and more particularly to systems in which connections are set up between exchanges over automatic selecting switches. The invention is especially applicable to systems in which 5 trunk calls are set up by an operator.

Although the invention is primarily concerned with trunk switching, several of its features are applicable to short inter-exchange switching.

10 The trunk system contemplated in this invention is one in which there are a number of trunk exchanges and in which the completion of a trunk connection may involve the serial connection of inter-exchange trunks. To one or 15 more of these inter-exchange trunks which are direct trunks between two exchanges, alternative routes involving a further exchange or exchanges are provided. A trunk connection is set up in stages and at each exchange at which automatic 20 switching apparatus is situated, digits characteristic of the next exchange through which the call would normally pass are received. To enable a flexible and economical layout of the 25 trunk selecting switches, translating arrangements are provided and this permits the digits assigned to an exchange to bear some resemblance, if desired, to the exchange name. For 30 this to be carried out register sending and translating arrangements are provided in the trunk exchanges. The provision of such arrangements besides dealing with calls originating at the several exchanges enables an indirect or alternative route between normally adjacent exchanges to be 35 selected automatically at any stage of a connection should no direct inter-exchange trunk be free and enables additional impulses to be generated automatically and transmitted for setting 40 automatic selecting switches in exchanges in the indirect route. It is a feature of the invention that group control arrangements are associated 45 with the several trunk groups which so control the register sender that a transmission of digits for selecting an alternative route involving a further exchange takes place without loss of time due to search having previously to be made 50 in a group of direct trunks to determine that all such trunks are busy. The group control arrangements are continuously operative so that when a register sender has received the digits 55 denoting the exchange to which the connection is to be extended, the translating arrangements test for an indication of the condition of the trunk routes available and transmit the route selecting digits for the free route, preference being given to the direct trunk route, im-

mediately. The translating arrangements may be such that simultaneous translations for each route are made, the translation to be made effective depending on the result of the test by the translating arrangements. The arrangements 5 also provide for routing the call to a storage equipment in case of congestion in trunk routes and may also provide for routing a call to a manual board position should difficulty be experienced in selecting a route automatically. 10 The whole or a part of a connection may be set up by an operator at the trunk exchange at the centre at which the call originates.

In a trunk system, especially in one that is in 15 a state of development, some of the exchanges may be manually operated. In such a case the arrangements may be employed at those exchanges possessing automatic switching apparatus, the seizure of a trunk resulting in the signalling of an operator at the manual exchange. 20 The operator so signalled would then complete the setting up of the connection in the usual manner.

As regards control of the trunk selectors the 25 use of group control in conjunction with the translating arrangements obviates search over busy outlets to direct trunks before making a search in a group of alternative route trunks, the selecting switch being directed immediately to a group in which it is known that a free 30 outlet will be found. Should the only free outlets in this group be taken before a searching 35 selecting switch reaches them, arrangements for dealing otherwise with the call become operative. Thus the call may be routed to a manual board 40 at the point at which congestion is encountered but if this point is at an exchange in an indirect route it may be more convenient to release the connection back to the point of diversion from the direct route and call in the aid of an operator 45 at the trunk exchange at that point. At an exchange at which an operator sets up the whole or a part of a connection, hereinafter referred to as an originating exchange, it may be more 50 convenient to release the indirect route set up and direct the switches again to outlets of a direct route, arrangements being made for storing the call. Congestion at first and incoming trunk selectors searching for an outlet to a second selector may be dealt with by causing the selector to make a further search in the same 55 group after the lapse of a time interval, a second failure to find a free outlet causing the connection to be routed to a manual board. Group

control arrangements enable these facilities to be carried out.

The trunks used in an indirect route may be the same as those normally used in a direct route 5 between the pair of exchanges in question and as such may appear only once in the selecting switch multiple. As regards the connection of trunks in the banks of the trunk selecting switches, these may be connected in any convenient manner and the position in the selector banks of trunks of an indirect route need bear no particular relation to that of the direct trunks to which they offer an alternative and may even be taken from different groups of selecting 10 switches. 15

The register sending and translating arrangements, which also include the apparatus responsive to received digits differ somewhat according to whether they are required to deal 20 with digits originating at the exchange at which they are situated or with digits incoming over a trunk from a preceding exchange. In general the digits at an originating exchange may be transmitted from a key sender direct to registers 25 while digits incoming from another exchange may be in the form of impulses, either makes end brakes of a circuit over one or both of the line wires, or the transmission thereover of pulses of alternating current of suitable frequency. 30 While the general method of translation and digit sending may be similar in the two types of register sending apparatus, different methods of control may be required, as for instance in the one case no reversion of the call to a preceding 35 exchange will be required.

In carrying out the invention it may be arranged that all trunk lines are connected in the banks of second trunk selectors access to which is had over first or incoming trunk selectors. 40 In addition to outlets to second trunk selectors the first or incoming trunk selectors may have outlets to local selectors for the completion of calls locally. To reach the next trunk exchange through which a call must be set up there may be a group of direct trunks and a group of indirect trunks involving one or more additional exchanges. This latter group besides serving as indirect trunks to a more distant exchange may serve as direct trunks to a nearer exchange and would normally be considered as such. Accordingly 45 they may be taken from the same or different groups of second trunk selectors. In the second trunk selector each group of trunks has a call storing position to which the switch proceeds if at the time of search it is unable to find a free trunk. The arrangements provide that if the selector is searching a trunk group as an indirect route the call is not stored but the switch is stopped on some other contact and a signal is reverted, for example, by the application of a suitable potential to one of the marking wires, to the register sender to bring about release of the connection so far set up in the exchange in question and cause an attempt to be made to set up 55 a direct trunk connection. However, since all the direct trunks are engaged, the second trunk selector advances to the storing position and the call is stored. In the case of an exchange other than an originating exchange it may not be convenient 60 to store the call and provision may be made in this case to route the call to a manual operator. If it is known at the time the digits characterising the next exchange along the route are received that no free trunks of either kind 65 are available, the call may be routed immediately 70

to the manual operator. The first trunk selector is provided with an overflow outlet to which it proceeds if all the outlets in the desired direction are busy and from which a signal is sent to the register sender to bring about a further search 5 after a time interval. On reaching the overflow outlet for the second time the circuit arrangements may provide for the release of the sender and the transmission to the operator of an appropriate signal. 10

The first trunk selectors are connected directly to a connecting circuit, and the common apparatus for the control of a number of selectors may be situated in a common position circuit. The position circuit also includes a key strip and relays 15 for changing over the wires to the register sender from the key strip to the selector circuit. 20

The second trunk selectors also may have only a small amount of apparatus individual to them, circuits common to a number of selectors and associative with any one of them containing the apparatus necessary for the control of the setting of the selectors. Both the first and second trunk selectors are adapted to be set by the marking method. 25

Routing relays operated under the control of group control arrangements provide for the application of marking connections for the control of the selectors concerned to cause them to search directly among outlets in which it is known that 30 a free outlet is available at that time. The marking connections for the direct and indirect routes may include different wipers of a translating switch in the register sender. At an intermediate exchange the register sender is adapted to receive 35 a signal that congestion has been encountered and depending on which the register sender is at an exchange in a direct or indirect route to route the call accordingly. 40

A specific embodiment of the invention as applied to a system in which all the trunk exchanges contain automatic switching apparatus will now be described, the digit registering and sending arrangements being illustrated in the accompanying drawings. Of these Figs. 1-8 show register 45 sending arrangements for use at an originating exchange, Fig. 9 shows so much of an incoming selector at an intermediate exchange as is necessary for the understanding of the invention and Figs. 10 and 11 show register sending arrangements at an incoming exchange. For the sake of example it has been assumed that all the digits necessary for the setting up of the connection are transmitted from the exchange at the centre from which the call is made. With regard to the arrangements at an originating exchange, it should be explained that calls from a subscriber in the area in which the originating exchange is situated are distributed by means of automatic distributor switches to operators' positions. An operator's 50 position has a cordless connecting circuit the incoming side of which is connected to the multiplied contacts in the banks of the distributing switches and the outgoing side of which is connected to a first trunk selector. The connecting circuit 55 includes relays for splitting the circuit and connecting the two sides to a position equipment common to all the connecting circuits of an operator's position. The position equipment includes supervisory listening, speaking and monitoring 60 equipment, a set of digit keys by means of which the operator may key up any number for transmission to the register sender, and a dial for transmitting impulses over trunks to other exchanges. It also includes keys for the control 65 70

of relays in the individual connecting circuit and a lamp which indicates to the operator the condition of any group of trunks, the code designation of which she has transmitted by her keys to the 5 register sender. The first trunk elector is a 100-outlet single motion motor-driven switch which gives access to second trunk selectors and to link circuits leading to local automatic selecting switches for the completion of calls within the 10 local area.

The first trunk selector is set by markings applied by code relays which are operated singly or in combination by code signals transmitted from the register sender. For the transmission 15 of digits to the register sender the digit key strip is connected to the signalling wires denoted by W, X, Y, Z in Fig. 1, and when the transmission of digits from the sender is to commence the digit key strip is disconnected from the signalling 20 wires and the latter are connected to one or other side of the connecting circuit, depending on the keys thrown by the operator. For the purpose of the present description it will be taken that the signalling wires are connected to that side 25 of the connecting circuit connected to the first trunk selector. To this connection are connected the four code marking relays for receiving the code marking and for marking the first trunk selector accordingly. At the end of the bank 30 of the first trunk selector are situated overflow contacts to which the wipers rotate and on which they are brought to rest if search in the marked group has been unsuccessful. In this position a signal in the form of battery potential is transmitted 35 over the wire Y to the register sender to bring about results which will appear in the detailed description to follow. The complete circuit arrangements of the connecting and position circuits of the first trunk selector are assumed to 40 be as described and shown in British specification No. 8,378/36.

Access to trunk lines is had over a second trunk selector. This is also a motor-driven single motion 100-outlet switch with a common control 45 circuit. Like the first trunk selector it is set by a marking applied by code relays situated in the common control circuit. In the banks of this selector are connected trunks to adjacent exchanges i. e., exchanges next to be encountered 50 in the setting up of a trunk connection to a more distant exchange. The direct trunks to one exchange may serve as trunks in an indirect or alternative route to another exchange. Thus, if the selector is situated at exchange A and 55 there are direct trunks to exchanges B and C, and there are also direct trunks from exchange B to exchange D and from exchange C to exchange B, the normal route for a call to exchange D would be over the trunks A—B and B—D. If 60 the route A—B is busy an indirect or alternative route A—C, C—B, B—D may be taken, for which purpose one of the ordinary trunks for calls to exchange C may be used. An alternative route between exchanges B and D may include an 65 exchange E. The system however is not limited to the case in which there may be only one exchange in an indirect or alternative route. In each outlet to a trunk line is connected a relay set for transmitting signals and impulses over 70 the trunk as alternating currents of a frequency within the speech range (voice frequency signals). The arrangements also provide, as will be clear from a consideration of what is to follow, that the alternative route trunks for any connection 75 may be taken from a different group of second

trunk selectors from that giving access to the direct route trunks. The second trunk selector is also provided with contact positions at the end of its bank giving access to call storing equipment associated with each trunk group and arranged 5 to be taken into use if no direct route trunk is free at the time the wanted group is searched. Provision is made for supervisory signals to be transmitted and in the case of a call being stored, for signalling to the operator when a free 10 trunk in the desired direct route becomes available so that the selector may be again set in motion to search for it.

The second trunk selector is caused to search in either a group of direct route trunks or a 15 group of alternative route trunks in accordance with a signal received from the register sender. If it searches a group of trunks to which there is no alternative route and congestion is encountered the call is stored. If there is an alternative route and all the trunks in the direct route are busy, the latter are not searched but the trunks of the alternative route are searched. If at the time of search these are all busy, the 20 switch is brought to rest on overflow contacts different from those connected to the storing positions. The call is not stored but a signal is transmitted by a battery connection to the wire corresponding to Y in Fig. 1 to the register sender to bring about release of the connection so far 25 set up and the setting up of a connection to the direct group of trunks. Since this group is busy the call will be stored as in the case of a trunk group to which no alternative route is provided. 30

The circuits shown in Figs. 1-8 will now be 35 described. These figures should be arranged with Figs. 1-4 in order and Figs. 5-8 in order below them. The register sender which is assumed to be in exchange A is one of a number connected to a chain circuit, the wires of which designated "In" and "Out" will be seen to the left of Fig. 5. The register sender is connected to a connecting circuit when required by means of a coupling switch SC. This is a latch-controlled 40 motor-driven single motion 50-point switch with 8 wipers and associated contact arcs. Only the latch magnet is shown and this is designated SCM. The construction and method of operation of such a motor mechanism is now well known in the art and hence for the purpose of this description only the latch magnet will be considered.

The incoming signalling wires W, X, Y, Z are connected to wipers of a controlling switch which is a pawl and ratchet stepping 45 switch of the reverse drive type. Its magnet is designated DDM and its wipers DD₁—DD₈. This switch serves to direct the incoming keyed up digits to the several registers in turn and afterwards to connect the registers to the signalling wires for the transmission of the code digits for 50 the setting of the trunk selectors at the same exchange. The registers are of the relay type, each comprising four relays. The relays of the first register are designated AW, AX, AY, AZ, and those of successive registers BW—BZ, 55 CW—CZ, DW—DZ and EW—EZ respectively. There is a further motor-driven switch for effecting translation for the received code digits. The motor mechanism of this switch is indicated by its latch magnet designated CMU and its 60 wipers are designated CM₁—CM₈. The contact arcs of wipers CM₁—CM₈ are connected to terminals 1 to 8 in a manner which provides for the translation of the digits setting the switch 65 and for a suitable marking of the signalling 70 wires. The contact arcs of wipers CM₁—CM₈ are connected to terminals 1 to 8 in a manner which provides for the translation of the digits setting the switch and for a suitable marking of the signalling 75

wires. The translating switch CM is set in accordance with a marking applied by the relays of the first two registers. The switch, in accordance with its setting also connects relays PY, SY and DG to three group control wires the condition of which is determined by the condition of the corresponding trunk groups and by a supervisory key, the throwing of which denotes that all calls are subject to delay and that delay working by the operators in force. A further pair of stepping switches of the pawl and ratchet type and designated SM and SN serve as a sender for the sending of loop impulses over wires W and X for the setting of local automatic selecting switches. Of the relays shown the principal are the high speed test relays TC and T for the switches SC and CM respectively, the release control relay B, auxiliary release control relay BA, start relay ST, start sending relay SR, change-from-code-sending-to-impulsing relay SS, first trunk selector re-search relay RL, trunk group re-search relay RS and cut-off relay CO. Relays ZA and ZB are impulse marking relays and relays PD, RP, RQ and SX are concerned with impulsing. Relay Y is an impulse generating relay which generates the impulses for stepping the switches SM and SN and in certain circumstances the switch DD, and by means of its contact y_1 opens and closes the wires W and X for the transmission thereover of impulses. Relay RA is a release alarm relay connected in series with the two switch motors and relay RB is a release alarm relay having one winding connected in series with the stepping switch magnets. The functions of the other relays not specifically outlined at this point will be apparent from the following description. Contacts $scon$ and $cmon$ are off-normal contacts of switches SC and CM respectively, contact ddm is an armature operated contact of magnet DDM and contacts smm and snm are similar contacts of magnets SMM and SNM. In order to simplify the drawing points indicated by like numerals enclosed in circles are assumed to be joined together.

An operator at the exchange at which the register sender of Figs. 1-3 is situated having received a demand for a trunk connection refers to her routing table to ascertain the exchanges through which the call will have to pass to reach its destination. She associates her position apparatus with a free first trunk selector, marks the position in the bank of the coupler switch associated with the register sender and causes a start signal to be sent over wire "In" to the register sender. In the register sender, relay C is normally operated in a circuit from earth over key BK, contacts b_6 , c_03 , the relay winding to battery and the "In" wire is connected over contact c_1 to relay ST. The starting signal transmitted by the action of the operator accordingly operates relay ST. Contact st_1 prepares a testing circuit for switch SC, contact st_2 completes a circuit for relay SH if the coupling switch SC happens to be on any contact other than zero, contact st_3 completes a circuit for the coupling switch latch magnet over contact tcl and the motor is started. Battery to the latch magnet and motor is fed over relay RA. Contact st_4 lights the pilot lamp PL. The switch SC is rotated until the marked position is reached whereupon the high speed test relay TC operates, the circuit being from earth over contact st_1 , the metal rectifier, both windings of relay TC in series, wiper 8 to battery on wire P. Contact

tcl opens the driving circuit and the switch is brought to rest. When the switch was started or as soon as it left its zero contact position if it starts from this position, contact $scon_2$ was opened and relay SH operated and locked up over contacts sh_1 and b_3 . If the starting signal should be removed before the marked position is met by the switch, the switch continues to rotate until the zero position is reached by reason of a circuit for the magnet SCM over contact st_3 , sh_2 and $scon_1$, the last-mentioned contact being closed whenever the switch wipers are away from their zero position. When the switch reaches its zero position the magnet circuit is opened at contact $scon_1$ and relay SH is short-circuited at contact $scon_2$ to bring about its release.

Earth over wire P operates a relay in the position circuit to connect the digit key strip to wires W-Z and to open the circuit for relay ST. The right-hand high resistance winding of relay TC and rectifier are short-circuited by contact tcl and a short-circuit is removed from the upper winding of relay B. Relay B operates in series with magnet SCM and holds to battery over contact b_4 . Contact b_1 connects a holding earth for the register relays, contact b_2 disconnects winding (I) of relay CO from commoned contacts in the bank of wiper DD7, contact b_3 releases relay SH and prepares a holding circuit for relay B and for a relay in the position circuit, contact b_5 connects earth to magnet DDM, contact b_6 releases relay C and connects earth over key BK to maintain the lamp PL glowing and contact b_7 connects a general holding earth over contact ck_3 for many of the relays. Relay BA operates. Contact ba_2 closes in the circuit over wiper 7 and contact ba_3 connects relay ZS to a time pulse circuit. Relay C releases and connects wire "In" to wire "Out" to direct the next call from any position to the next register sender in the chain circuit. Relay ST releases. The distributor takes one step, its magnet circuit being from earth over contact b_5 , contact O and wiper DD1, contact ddm of magnet DDM, contact r_12 , magnet DDM, low resistance winding of relay RB to battery. When the magnet armature is attracted contact ddm opens and releases the magnet and the wipers are stepped to contacts 1. There being no earth over contact 1 in the bank of wiper DD1 the switch remains in this position. Whenever relay RA is operated, contact ra_1 closes a circuit for the high resistance winding of relay RB and whenever relay RB is operated contact rb_1 closes a circuit for a delayed alarm, contact rb_2 disconnects lamp PL from steady earth and connects it to a source of intermittent earth and contact rb_3 is included in the releasing circuit for relay CO to hold this circuit open until all the switches in the register sender have been restored to normal. In position 1 of the distributor, wires W-Z are connected over wipers DD2-DD5 to the register relays AW-AZ.

It will first be assumed that there is a direct trunk free and available to the next exchange on the route to the required destination and that there is no alternative route.

The operator keys up the digits indicative of the next exchange along the direct route. This designation comprises two digits. The first digit operates one or a pair of the relays AW-AZ. It may here be remarked that the digit 1 represented by a marking on wires W and X is reserved for calls to a local automatic exchange. The

relays responsive to the marking applied by the first digit key depressed operate over their left-hand windings and lock up over their right-hand windings, their contacts s_1 and contact b_1 . In the 5 operating circuits for the register relays relay DS operates over its right-hand winding. Contact ds_1 closes a circuit for magnet DDM, the magnet operates and on the release of relay DS, which occurs when the digit key is released, steps 10 the distributor to its second position in which the register relays BW—BZ are connected to wires W—Z. The second digit is registered, the relays locked up and the distributor is stepped to position 3. A third digit, the numeral 1, is keyed up 15 to cause the second trunk selector to search and register relays CW and CX are operated and locked up and the distributor steps to position 4. Contacts of the two registers set by the first two digits are connected between banks of the translating switch CM and provide a marking for the setting of that switch. Since one of the relays AW, AX will not have been operated a circuit is closed in position 3 of the distributor from earth over contacts ck_3 , b_1 , wiper DD6, contact aw_3 or 20 ax_3 , right-hand winding of relay CS to battery. Relay CS operates and locks up over its left-hand winding, contacts cs_2 , b_1 and ck_3 to earth. Contact cs_1 disconnects contact t_0 in the bank of wiper DD7 from commoned contacts 1 to 9, 11 25 and 16—24 and connects it to a set of contacts of the register relays CW—, DW—, EW—, contact cs_3 prepares a circuit for test relays TS and TT and with contact cs_4 opens circuits that might otherwise exist for these relays over contacts aw_2 and ax_2 , contact cs_5 closes a circuit for latch magnet CMU and contact cs_6 connects earth over wiper DD6 when it reaches position 4 to the right-hand winding of slow operating relays AS. The latch magnet CMU operates in a circuit from 30 earth over contacts t_1 and cs_5 in series with relay RA and the translating switch is driven in search of the marking applied by the registers. This marking is battery over wiper CM12, contacts of the registers AW—AZ and BW—BZ and a contact in the bank of wiper CM13. When this 35 marking is encountered, relay T operates and at contact t_1 opens the circuit for CMU thereby bringing the switch to rest and closes the circuit of relay CT. Relay CT operates and at contact ct_1 connects relay DG to wiper CM9 to 40 determine whether delayed working is in force on this particular trunk group or not, at contacts ct_2 and ct_3 prepares circuits over wipers CM10 and CM11 to route-determining wires, at contact ct_4 prepares a circuit for relay FY and at contact ct_5 completes the following circuit: earth, over wiper DD6, contact cs_6 , right-hand winding of relay AS, contacts dg_2 , ct_5 to battery. If delayed working is not in force relay DG will not 45 be operated and relay AS will operate in the above traced circuit. Contact as_1 closes a circuit for right-hand winding of relay SR and contact as_2 connects earth over wiper 2 of switch 50 SC to wire D to operate a relay in the position circuit to bring about the disconnection of the digit key strip and the connection of the signalling wires W—Z to the first selector code marking relays. The relay in the position circuit 55 connects a high resistance winding to wire P over which it holds but relay TC in series with it does not receive sufficient current to maintain it and it releases. Relay SR operates. It may here be remarked that the two windings of relay 60 SR are wound differentially and the relay will not 65 70 75

operate due to the energisation of both windings in series. Furthermore, relay CK which is connected in series with the right-hand winding of relay SR and in parallel with its left-hand winding will not operate in this circuit. As a result 5 of the operation of relay SR the relay locks up over contact sr_1 independently of contact as_1 and the connection to relay CK is opened: contact sr_2 prepares a stepping circuit for switch DD, contact sr_3 connects up the lower winding 10 of relay B over contacts co_2 and b_3 , relay B holding until this connection is made by reason of its upper winding being short circuited over contact tc_1 . Earth over contact b_3 and the winding of relay TC holds relay B by means of its 15 lower winding and the relay in the position circuit connected to wire P. Contact sr_4 completes the circuit of relay S and contact sr_5 opens the circuit of the right-hand winding of relay DS. Relay S operates. Contact s_1 connects battery 20 over relays TS and TT to those wipers of CM1—CM8 connected up by the operated primary routing relay PY, contact s_2 prepares a connection for relay SS, contact s_3 completes the previously prepared stepping circuit for the distributor and closes a circuit for the lower winding of relay PY, contact s_4 opens in a path over wire Y, a parallel path being maintained closed over contact ds_3 , and contact s_5 closes in a circuit for relay CO. Magnet DDM operates in a 25 circuit from earth over contacts s_3 , sr_2 , wiper DD1 and contact ddm and the switch is stepped by self-interruption of the magnet circuit until position 7 is reached. In this position wires W—Z are connected over wipers DD2—DD5 to 30 terminals of the cross-connecting frame cross-connected to the translating banks of the translating switch. Contact 7 in the bank of wiper DD6 is so connected to relay RL to bring about the timing of an interval before a re-search by 35 the first trunk selector if the latter meets with congestion.

Relay PY operates, locks up over contact py_1 and at that contact opens a possible operating circuit for relay SY. A further operating circuit 45 for relay SY is opened at contact py_2 . Contact py_3 disconnects relay RS from contact 9 in the bank of wiper DD6, and contacts py_4 , py_5 and py_6 complete the connection of relays TS and TT to wipers CM1, CH2 and CM4. The digit for 50 setting the first trunk selector in a direct route is marked in the banks of wipers SM1 and CM2, and the digit for setting the second trunk selector in a direct route is marked in the banks of wipers CM3 and CM4. The corresponding 55 digits for the marking of an alternative route are marked in the banks of wipers CM5, CM6 and CM7, CM8 respectively. A circuit or circuits now exist from earth over the several code marking relays in the position circuit, one or a pair of the 60 wires W, X, Y, Z, wipers DD2—DD5 in position 7, terminals 1—4 of the connecting field, wipers CM1 and/or CM2, contacts py_4 , and/or py_5 , cs_3 , ds_4 , s_1 , relays TT, TS, contact t_1 , to battery. The code relays are operated in series with relays TT and TS. Relay TS is very quick to operate and changes over its contact ts_1 before contact t_1 opens. When relay TT operates, contact t_1 and contact tt_2 prepares a circuit for the left-hand winding of relay DS. As a consequence of the setting of the first trunk selector in response to the applied marking, the circuit of the code marking relays is opened. Relay TS releases immediately and during the somewhat longer releasing time of relay TT a circuit for relay DS 75

is closed. The release of relay TT opens this circuit and releases relay DS. Relay DS by the operation and release of its contact *ds1* causes the distributor to take one step, contact *ds2* connects relay SS to wire Z in readiness to receive a signal denoting that further digits are to be transmitted as impulses, contact *ds3* connects relay RL to wire Y in readiness to receive a signal denoting a state of congestion and to initiate a pause after which a further search by the first trunk selector will be made, and contact *ds4* opens a further point in the circuit for relays TT and TS to prevent their re-operation until the distributor shall have stepped. The digit for marking the second trunk selector is transmitted in a similar manner to that for the first trunk selector over wipers CM3 and CM4 and their contacts cross-connected to terminals 5 to 8 of the cross-connecting field and wipers DD2-DD5 in position 8. Relay R operates in position 8 by means of its right-hand winding to release relay RM should it have been previously operated. After this marking has been transferred switch DD moves to position 9 in which a marking corresponding to the digit 1 is transferred to cause the second trunk selector to search in the group previously marked. The digit is transferred over relays TS and TT, contacts *cw2*, *cx2* and contacts 9 in the banks of wipers DD2 and DD3. Switch DD is stepped to position 10 in which earth is extended over wiper DD7 and contact *cs1* to winding (I) of relay CO. Relay CO operates and locks up over contact *co4*. Contact *co2* releases relay B and opens the circuit over wire P to the position circuit to give a signal to the operator that sending has finished. Contact *co3* maintains lamp PL lit and guards against re-operation of relay C until the register sender apparatus has been completely restored to normal and contact *co5* prepares for the release of relay CO.

Relay CO releases when all the apparatus in the register sender has been restored to normal and contacts *rb3* and *cmon2* are closed to short-circuit relay CO over wiper DD7.

Releasing circuits are closed as follows: for the distributor over contacts *b5*, *ss5*, *rs3* and wiper DD1 to magnet DDM and relay RB; for the translating switch by the release of relay CS at *b1*, contact *cs5* closing a circuit for magnet CMU and relay RA over off-normal contacts *cmon1*. Contact *b1* also disconnects earth from the several relays in the register sender and contact *b1* unlocks the register relays. When the switches have restored, contact *rb3* closes and contact *cmon2* being closed a short circuit is imposed across winding (I) of relay CO from earth over contacts *cs3*, *rs5*, *rl1*, wiper DD7 in its normal position and relay CO is released opening its releasing circuit at contact *co5* and re-connecting relay C at contact *co3*.

If the second trunk selector is not to search in a selected trunk group but is required to select a particular trunk in that group the third digit will be one of the numerals 2-0. The code marking will accordingly be transferred in the same way as for the numeral 1 but instead of the relays CW and CX being operated one of these relays or a different pair will be operated.

If an alternative route exists, relay PY will be operated as soon as the third digit is received on the register and relay CT has operated. It should be explained that the contacts in the bank of wiper CM10 are connected to wires which are earthed by a group control device so long as

there are direct routes available in the respective trunk routes. Similarly the contacts in the bank of wiper CM11 are earthed so long as alternative routes to the next exchange to be selected are available. Relay SY is slow to operate in order that preference may be given to the direct route. Accordingly when relays CW, CX and CT have operated, relay PY is operated over its upper winding and wiper CM10 and the circuit for relay SY over wiper CM11 is opened at contact *py2*. The setting of the first and second trunk selectors proceeds as described above after which the register sender is released. If all the direct trunks are busy but an alternative route is free, earth will be absent from the contact in the bank of wiper CM10 and relay SY will be operated by means of its lower winding. This will take place before relay S operated and contact *sy5* will prevent the subsequent closure of the circuit over the lower winding of relay PY when contact *s3* closes. Relay SY locks up over its upper winding and contacts *sy6* and *py1* at contact *sy4* disconnects relay PY from wiper CM10 to guard against the transference of a mutilated code should a direct trunk now become available. Contact *sy2* disconnects wiper CM3 of the translating switch and connects up wiper CM7, contact *sy1* prepares a circuit over wire Y for giving a signal to the second trunk selector that it is to search for an alternative route and that the call must not be stored if by the time this route is searched there should be no free trunk and contact *sy3* connects earth over wire C to give a signal to the operator to indicate to her that an alternative route is being taken. The first two digits are transferred as before in positions 7 and 8 of the controlling switch, the only difference being that the code marking relays to be operated depend on the marking applied over wipers CM5, CM6 and CM1, CM8 instead of a marking over wipers CM1-CM4. The code marking relays for the third digit are those connected to wires W, X and Y since these wires are marked in position 9 of the distributor over contacts *cw2*, *cx2* and *sy1*. If the alternative route is found free, the register sender is then released.

If the alternative route, although signalled free, is found busy by the time the second trunk selector tests the outlets of the route, the second trunk selector rotates to a predetermined contact position in which battery is connected to wire Y. The distributor will be in position 9 at this time and when as a consequence of the second trunk selector's being stopped on the predetermined contacts relay TS is released and relay DS is operated, relay RS is operated in a circuit from earth over wiper DD6, contact *py3*, winding (L) of relay RS, contacts *rm3*, *ds3*, *ss4* and wire Y to the aforementioned battery. Contacts *rs1* connects earth to wire S to bring about the opening of the code signaling wires in the first trunk selector circuit and the release of the first and second trunk selectors, contact *rs2* connects winding (II) of relay RS to the stepping circuit for magnet DDM, contact *rs3* connects earth to contacts 8 to 10 in the bank of wiper DD1 to cause the distributor to step to contact 11 and thence to contact O by reason of the extension of earth over contacts *rs3* and *ss5* to contact positions 11-24. On reaching contact O the switch is stepped on due to that contact being earthed over contact *b5*. Contacts 1-6 are earthed over contacts *sr2* and *s3*, and the switch self-steps to contact 7 where it is brought to rest. Contact *rs4* having closed, earth is extended to the lower

winding of relay PY and that relay is operated to release relay SY and to cause the direct route marking to be re-applied to the first trunk selector. Contact $rs5$ holds open the circuit for relay CO during the stepping of the distributor over contact 10. Relay RS is held during the stepping of the distributor by its winding (II) connected over contact $rs2$ to the self-stepping circuit. The distributor is now in position 7 and the first digit indicative of a trunk to the next exchange on the direct route to the call destination is transferred as before. The first and second trunk selectors are set in the normal manner but since there are no direct trunks available, the call is stored in a storage equipment particular to the trunks of the direct route and the register sender is released. If at the time relay CT operates there are neither direct nor alternative route trunks free and available and delay working has not been initiated, relay PY is operated by means of its lower winding over contacts $ct4$, $sy5$ and $s3$ to bring about digit transmission for routing the call to the direct route so that it may be stored.

25 It will now be clear that the direct and alternative routes, which are determined before search is made by the first trunk selector may be taken from different groups of second trunk selectors. In the case of a reversion from alternative to direct route such as has just been described, the first trunk selector is released and re-set so that a different group of second trunk selectors from that used for the alternative route may be employed.

35 It may happen that the first trunk selector is unable to find a free second trunk selector to deal with a call although there may be free trunks in the desired route from the groups of second trunk selectors concerned. The code marking for the first trunk selector is applied in contact position 7 to the distributor. If there is no free second trunk selector available in the marked group, the selector rotates to a congestion position in which battery is connected to wire Y. This battery connection completes a circuit for the left-hand winding of relay RL over contact 1 and wiper DD6 when relay DS operates. Relay RL locks up over its right-hand winding and contacts $rl5$ and $rm2$. Contact $rl1$ earths wire S to bring about release of the first trunk selector from the congestion position, contact $rl2$ opens the self-stepping circuit for magnet DDM, contact $rl3$ closes a circuit for relay Y, contact $rl4$ prepares a pulsing circuit to magnet DDM, contact $rl6$ prepares a circuit for relay RM and contacts $rl7$ opens the circuit over wiper DD7 to guard relay CO against operation when the wiper reaches contact 10. Y is a pulsing relay and operates by the slow-self-interruption of its own circuit. It has two windings, in the circuit of one of which is connected a condenser QG of a capacity suited to the pulsing speed required.

45 This condenser is also shunted, in the present use of relay Y by a further condenser QF over contacts $s24$ and $rl8$. When contact $rl3$ closes the condensers commence to charge and the current flowing in the windings of the relay produce opposing fluxes so that the relay does not operate immediately. As the condenser charging current dies down the flux produced by current in the right-hand winding of the relay predominates and the armature commences to move. When contact $y2$ is fully operated, the relay does not release immediately as the condenser commences to discharge through the two windings in series

5 and the direction of the current is such that the fluxes produced act in the same direction thus delaying the release of the relay. It will thus be seen that the pulsing time and duration will depend on the value of capacity connected in series with the left-hand winding.

55 For the purpose now being considered, viz: the stepping of the distributor, a speed of 10 impulses per second is suitable. When contact $y2$ is in its front position the following circuit is closed: 10 earth over contacts $ds1$, $rl3$, $vc1$, $y2$, $rl4$, $rm1$, magnet DDM, relay RB to battery. The magnet attracts its armature. When contact $y2$ opens the magnet releases its armature and advances the switch wipers one step. At each pulse given 15 by relay Y the distributor is advanced one step and this continues until the wipers have been stepped round the bank until they reach contact 6 thus measuring off a period of about 2.5 seconds. In this contact position a circuit is closed 20 over wiper DD6 and contact $rl2$ for the left-hand winding of relay RM. Relay RM operates and locks up over contacts $rl3$ and $rm2$. Contact $rm1$ opens to prevent a further pulse reaching magnet DDM and contact $rm3$ connects winding (II) of 25 relay CO to contact $ds3$ in readiness to receive a congestion signal. Contact $rm2$ opens the locking circuit of relay RL and that relay releases thereby opening the circuit for relay Y. Closure of contact $rl2$ completes a circuit over contacts 30 $s3$, $sr2$, and wiper DD1 for magnet DDM which by taking a single step brings the wipers again into the 7th position in which the first coded digit is once more transferred to the first trunk selector. If the selector is successful in finding 35 a free outlet, the second and third coded digits are transferred to the second trunk selector but if a congested condition is still encountered, battery will be applied to wire Y and relay CO operated to release the register sender. In position 40 40 of the distributor, relay R is operated to release relay RM at contact $rl3$ to enable relay RS to receive a signal over wire Y from the second trunk selector. By arranging for the release of relay RM on the release of relay RL an indefinite 45 number of searches by the first trunk selector at intervals may be had.

45 If traffic is very heavy in the trunk group over which it is desired that the call shall proceed, delay working may be put into operation. When this is done a key is thrown which connects earth to the relevant contacts in the banks of wipers CM9 and CM10 of the translating switch. When the translating switch has taken up its position determined by the operation of the relays in the first and second digit registers and relay CT has operated, relay DG operates over contact $ct1$ and wiper CM9 to the earth applied by the delay working key. Contact $dg1$ connects a flicker earth to wire C to indicate to the operator that delay working is in force on the trunk group concerned so that she may ticket the call and advise the caller accordingly. Contact $dg2$ opens to prevent operation of relay AS which would bring about a fruitless search by initiating the 60 transmission of the code marking digits. Since relay PY will be operated by the earth over wiper CM10 the operator can, by pressing a key, operate relay SR directly over wiper SC7 thereby starting digit transmission and causing the call 65 to be stored.

70 Should the operator inadvertently key up a dead number for the first two digits, the translating switch will not find a marked contact and will continue to rotate until the last contact posi- 75

tion is reached. It will be stopped in this position by the operation of relay T to battery over the wiper CM12. Relay RM will operate in a circuit from earth over its right-hand winding, 5 last contact and wiper CM9, contact *ct1*, relay DG to battery, but relay DG will not be operated. Relay RM locks up over its left-hand winding, and contacts *r3* and *rm2* and contact *rm3* prepares a connection for winding (II) of relay CO. A translation is provided for the first 10 digit and this is transferred to the first trunk selector which is rotated to a predetermined position in which battery is applied to wire Y.

When relay DS operates after the setting of 15 the first trunk selector the battery on wire Y operates relay CO by energising its winding (II) to release the register sender.

If the first digits are keyed correctly but a 20 third digit is keyed for which there is no corresponding trunk, all three digits will be transferred in the usual manner but the second trunk selector will continue to rotate to a last contact position where battery will be connected to wire Y. Relay RS however will not operate in this 25 instance as its circuit will be open at contact *py3* and release of the register sender will take place when the distributor is stepped to position 10.

On the assumption that a free trunk to a succeeding exchange along either a direct or indirect 30 trunk route has been found the release of the register sender automatically brings about the switching through of the operator's circuit to incoming apparatus at the distant end of the 35 trunk and the operator dials the code of the next exchange to be selected in the setting up of the required trunk connection.

The operation of the register sender in setting 40 up calls over local automatic switches will now be described. Such a call is indicated by the first digit being '1'. Up to four further digits may follow for the setting of the numerical selecting switches. The first register will record the numeral 1 by the operation of relays AW and AX 45 and these relays will lock up to earth over contact *b1*. Contacts *aw3* and *ax3* open and prevent the operation of relay CS in position 3 of the controlling switch. Contacts *aw2* and *ax2* provide a marking over wires W and X to operate 50 the code marking relays in the first trunk selector, indicative of a call to be extended to a group of first numerical selectors. Since relay CS is not operated the translating switch does not search. As many further digits as are necessary 55 for setting up the connection are keyed and transmitted to one or more of the registers BW—, CW—, DW—, EW—. Furthermore, since relay CS is unoperated relay AS will not be operated in position 3 of the distributor and sending will 60 be delayed until all the necessary numerical digits have been registered. If there are four of these, switch DD will be stepped to position 6 after the last has been recorded in which position relay AS will be operated by means of its left-hand winding. Relay AS at contact *as1* operates 65 relay SR which in turn operates relay S and transmission of the registered digits commences. If there should be less than four numerical digits for the call in question, sending will be started 70 by the operator pressing a start key. This causes a low resistance battery connection to be made to wire S which operates relay SR. The distributor is stepped to position 7 in which relays TS and TT are connected over contacts *cs3*, 75 *aw2* and *cs4*, *ax2*, to wires W and X and the first

digit is transferred to the first trunk selector. The selector searches for a free outlet to a first numerical selector. Such an outlet contains a relay arrangement which causes battery potential to be applied to wire Z. When such an outlet is found relay TS releases and relay DS operates and the battery over wire Z is extended over contact *ss3*, *s2*, *ds2* to winding (I) of relay SS. Relay SS operates and locks up over its winding (II) and early closing contact *ss1*. Contact *ss1*, *ss2*, *ss3* and *ss4* disconnect wires W—Z from wipers DD2—DD5. Contacts *ss1* and *ss2* connect wires W and X to a loop including relay VA at present short-circuited over contacts *sz1* and contact *y0*. Contact *ss5* applies earth over contact *rs3* and contact 7 in the bank of wiper DD1 to magnet DDM, to cause it to self-step the switch to position 8. A self-stepping circuit is closed over contacts 8—10 and contact *ss5* to cause the switch to drive to position 11 in which marking contacts in the banks of switches SM and SN are connected over wipers DD2—DD5 to earth over the locking contacts 1 of operated register relays and contact *b1*. Contact *ss6* closes a circuit over wiper DD6 in position 11 for relay SX which operates and locks up over contact *sz2*. Contact *sz1* starts relay Y pulsing by applying earth over contacts *sz5* and *vc1* and the circuit previously traced for this relay.

Switches SM and SN are stepping switches 30 stepped by pulses delivered by relay Y to their magnets SMM and SNM. Associated with these switches are relays ZA and SB which operate when a pair of marked contacts are simultaneously encountered by wipers 2 and 3 of the switch in 35 use. The switches are used alternately, the odd numbered numerical digits being marked in the banks of switch SM and the even numbered numerical digits in the bank of switch SN. Relays R, RP, RQ, SX and PD are concerned with the 40 alternate use of the switches. Relays VA, VB and VC are concerned with the changeover from one digit to the next and relay SZ is the usual stop relay. Two speeds of impulse sending are provided for, a speed of 14 impulses per second 45 and a speed of 10 impulses per second. The speed is controlled, as before mentioned, by the value of capacity in the circuit of the left-hand winding of relay Y and to reduce the impulsive speed for the setting of numerical selectors, which 50 might be required in some cases where junctions are involved, a further condenser QF is switched in parallel with condenser QG normally in the relay circuit by the operation of relay SD. Whether this relay shall operate or not is determined by the second registered digit by means 55 of a battery connection cross-connected as required to contacts of the register relays BW—BZ.

When relay SS has operated and has operated 60 relay SX in position 11 of switch DD, relay Y is started by closure of contact *sz1*. Contacts *sz3* and *sz4* connect relay PD to contacts 22—24 in the banks of wipers SM1 and SN1. At each pulse of relay Y, when contact *y2* closes, 65 a circuit is closed for magnet SMM, the circuit being from earth over contacts *sz1*, *sz5*, *vc1*, *y2*, *rl4*, *pd3* and *r1*. The magnet operates and on the release of relay Y the switch magnet armature falls back and steps the switch. At each pulse 70 of relay Y the loop over wires W and X is opened at contact *y1* and an impulse is transmitted to the numerical selector connected to these wires. If four numerical digits are to be transmitted contacts in the banks of wipers SM2 and SM3 75

will be marked for the counting of the first digit by earth over contact *b1*, locking contacts *1* of the operated register relays BW—BZ and wipers DD2—DD5. For the sake of example it will be assumed that the first digit is 5. Relays BX and BZ will be operated and contacts *5* in the banks of wipers SM2 and SM3 will be marked. Although contact *4* in the bank of wiper SM3 will be marked over wire X and relay ZA will operate in this position of the switch, the stop relay SZ will not operate to stop impulse transmission. For this relay to operate relays ZA and ZB must both be operated and the markings of switches SM and SN are such that this can only occur in one position for each numeral. Switch SM is accordingly stepped until a position is reached in which both relays ZA and ZB operate. A circuit is now closed over contacts *1* of these relays and contact *vc3* for relay SZ. Relay SZ operates and at contact *sz1* short-circuits contact *y1* to prevent the transmission of further impulses over the outgoing loop. Contact *sz2* completes a holding circuit for relay SZ over contact *b5* to be operative after relays ZA and SB release, contact *sz3* closes a further holding circuit dependent on the counting switches, contact *sz4* disconnects condenser QF from the circuit of relay Y and connects it to a discharging circuit and the pulsing speed of relay Y is increased, contact *sz5* opens the pulsing circuit for relay Y and prepares a circuit including the left-hand winding of relay VC, and contact *sz6* closes a self-stepping circuit for switch SM. Magnet SMM operates in this circuit from earth over contacts *sz6*, *rp3*, magnet-operated contact *smm*, contacts *1*—*10* and wiper SM1 and advances the wipers rapidly to position *11*. In position *11* relay PD operates by the energisation of its high resistance right-hand winding in series with magnet SMM in a circuit including contacts *sz4*, *rp2* and wiper SM1. The switch magnet does not operate in this circuit. At contact *pd1* the further locking circuit for relay SZ is closed, at contact *pd2* the pulsing circuit for relay Y is re-closed and at contact *pd3* the right-hand winding of relay PD is shunted by the low resistance left-hand winding of the relay and magnet SMM now operates and is stepped by the now rapidly pulsing relay Y to its normal position.

If the loop over wires W and X extends metallically to the numerical selector which has just been set, the momentary break or increased inductance in the circuit caused by the operation of the switching relay thereat effects the release of relay VA which was operated over the loop in series with the impulse receiving relay. Relay VA was short-circuited during impulse transmission and was switched into circuit on the operation of relay SZ. It is a very sensitive relay and will release under the change of loop condition above referred to. When it operates a charging circuit for condenser QH is closed over contact *va1* and when it releases the charged condenser is discharged over the winding of relay VB. Relay VB is a fast relay and at its contact *vb1* connects up a holding circuit for itself and an operating circuit for relay VC. Relay VC operates due to the energisation of its right-hand winding and contact *vc2* substantiates contact *vb1*. Contact *vc1* opens the pulsing circuits for relay Y and magnet SMM, contact *vc3* opens in the operating and temporary holding circuits for relay SZ and extends earth by way of contacts *b5*, *sz2* and *rl2* to magnet DDM causing it to operate and contact *vc4* closes a circuit for the

left-hand winding of relay RP. The rapid pulsing of magnet SMM ceases and contact *rp2* changing over on the operation of relay RP recloses the self-stepping circuit for switch SM which continues to be stepped by self-interruption to normal. Relay RP holds by means of its low resistance right-hand winding connected in the self-stepping circuit of magnet SMM by contact *rp3*. The operation of relays VC and RP opens the circuit for relay PD and this relay releases and releases relay SZ. Contact *sz1* falling back short-circuits relay VA and re-connects contact *y1* in the impulse transmitting loop and contact *sz5* releases relays VB and VC and recloses the pulsing circuit for relay Y. Contact *sz4* prepares to re-connect condenser QF to bring the pulsing speed again to 10 impulses per second. Contact *sz2* opens the circuit for magnet DDM and that magnet releases and steps the distributor to position *12*. In this position the marking for the second numerical digit is connected up and relay R is operated over wiper DD6. Contact *rl1* disconnects the pulsing circuit for magnet SMM, and connects it to magnet SNM, and contact *rl2* changes over to prepare a circuit for relay RQ to be closed consequent on the second numerical selector switching through. Contact *rl3* is without effect at the present stage of operations. Switch SN is now stepped in a similar manner to that described for switch SM in search of a marking applied by the operated register relays of the set CW—CZ. When this marking is reached, relays ZA and ZB operate as before and impulse transmission is stopped by the operation of relay SZ. Switch SN is stepped to position *35* by self-interruption and after the release of relay VA and operation of relay VC relay RQ is operated and the switch continues to self-step to its normal position. Meanwhile magnet DDM has been operated and relay PD having been operated and subsequently released the distributor is stepped to position *13*. Relay R releases and the pulsing circuit is disconnected from magnet SNM and connected to magnet SMM. The third numerical digit is transmitted under the control of switch SM and after its transmission the distributor is stepped to position *14* in which relay R is again operated. The fourth numerical digit is transmitted under the control of switch SN. After its completion the distributor is advanced to position *15* in which a circuit is completed over wiper DD7 for relay CO to bring about the release of the register sender. In the connection between the trunk selectors and the local automatic switches is connected a link circuit which normally presents a metallic pulsing loop to the local switches. When relay CO operates, contact *co1* connects wire Z to wire Y over contact *ss3* whereby battery connected to wire Z in the link circuit as a consequence of a relay operation when the link was taken into use is applied to wire Y to bring about the connection of a feeding bridge into the circuit.

If it should happen that one of the digits is of a low value and relays RP and RQ are operated at the same time, relay SZ is held over contacts *rp1*, *rl1* independently of relay PD until one of the relays RP and RQ is released.

If pulsing is to be carried out at 10 impulses a second, this will be determined by the first numerical digit. The first numerical digit will be transmitted at the higher speed as it has been assumed that the first numerical selectors will be in the same exchange as the trunk selector or accessible over a short junction. When the dis-

tributor has been stepped to position 12 for the transmission of the second numerical digit and this and succeeding digits are to be transmitted at a lower speed, a circuit will be provided over 5 wiper DD7 in position 12 for relay SD over appropriate contacts of relays BW-BZ to battery. Relay SD operates due to the energisation of its left-hand winding in this circuit and locks up over its right-hand winding and contact *sd1*. 10 Contact *sd1* connects condenser QF in parallel with condenser QG to reduce the pulsing speed.

If a metallic circuit does not extend to the numerical selectors of a rank the arrangements for the immediate re-commencement of 15 pulsing after switching through cannot be employed. In such case the pulsing of the counting switch magnet continues until a predetermined position is reached. For the first two numerical digits this is position 22 of the counting switch 20 and for the last two digits it is position 14. In each of these positions a circuit is completed from earth over contacts *sx1*, *s25*, left-hand winding of relay VC, wiper DD8, the appropriate contacts of the distributor and counting switch, 25 relay ZA to battery. Relay VC operates but relay ZA does not. Relay VC thereupon performs the functions which it would have done earlier had relay VA been operative. The reason why this action occurs earlier in the case of the third 30 numerical digit is because no hunting time has to be allowed for, the fourth numerical digit being taken on the same final selecting switch as the third.

Should there be less than four numerical digits 35 to be transmitted, release of the register sender will be brought about automatically after the transmission of the last digit as follows: Contacts 12, 13 and 14 in the bank of wiper DD7 are connected to relay CO over serially connected 40 contacts of the corresponding register relays, so that whenever a digit is to be transmitted at least one of these relays will be operated and the circuit for relay CO opened. If less than the full number of digits is to be transmitted, none of 45 the relays of one or more of the registers will be operated, consequently in the appropriate position of the distributor a circuit will be closed for relay CO and release of the register sender brought about.

50 When the register sender is taken into use and relay BA is operated, contact *ba3* connects the left-hand winding of relay ZS to an earth pulse circuit. Relay ZS operates and locks up over its right-hand winding and contacts *zs1*, *b1* and *ck3*. 55 At contact *zs2* the pulsing machine is started and after an interval earth is applied momentarily over contact *s23* to relay ZZ if sending has not already commenced. Relay ZZ operates when the momentary earth is applied and at contact *zz1* applies earth over wiper 2 and wire D to give 60 a signal to the operator and contact *zz2* earths wire S thereby operating relay CK. Contact *ck1* opens the circuit over the left-hand winding of relay SR, contact *ck2* opens the circuit over the right-hand winding of relay SR and contact *ck3* disconnects the general holding earth and closes 65 a circuit for winding (I) of relay CO which operates and brings about the release of the register sender.

70 The operator may cancel any setting effected and release the register sender at any time by depressing a cancel key which applies earth to wire S to effect the operation of relay CK. If key ITK be thrown relay VA is disconnected and condenser QF is connected in parallel with condenser QG independently of contact *sd1*. The condenser 75

and resistance across contact *y1* is disconnected so that a test of the impulsing speed may be made without any influence on it or the character of the impulses and contact 13 in the bank of wiper DD8 is disconnected from contact 14 in the bank 5 of wiper SN2 and connected to contact 22 in the same bank to provide the same pause after the third digit as that after the first and second digits. Impulsing will then take place at the rate of 10 impulses per second irrespective of the 10 route to be taken.

Key BK is provided for busying the sender to position circuits. When thrown it disconnects relay C causing the chain start circuit to be extended to the next sender in the chain and lamp 15 PL is lit.

On the assumption that a free trunk to a succeeding exchange along either a direct or alternative route has been found, the release of the register sender automatically brings about the 20 switching through of the operator's circuit to the trunk line. Each trunk line has at its outgoing end a relay set adapted to transmit alternating current signals of two different frequencies with-in the speech range. One of these frequencies 25 which will be referred to hereinafter as "X" frequency is used for signalling in a forward direction and the other which will be referred to as "Y" frequency is used for signalling in a backward direction. When a trunk is taken into use 30 a pulse of current at "X" frequency is transmitted from the relay set to take the incoming apparatus at the distant end of the trunk into use. The operator now dials the code of the next exchange to be selected in the setting up of the required 35 trunk connection and the dialled impulses are received in the relay set where they are converted into pulses of current at "X" frequency and transmitted over the trunk to the apparatus at the distant end. At the distant end of the 40 trunk will be connected an incoming selector 45 adapted to receive and transmit voice frequency signals and adapted to be associated with the incoming selector is a register sender including translating arrangements for determining the trunk route to be selected and for governing the disposal of the call in certain circumstances.

The incoming selector may be a switch of a kind similar to the first and second trunk selectors previously referred to. The circuit arrangements necessary for the control of the selector in accordance with the present invention are shown in Fig. 9 of the accompanying drawings. This figure however, only shows so much of the circuits of the selector as is necessary for 55 the understanding of this invention. In Fig. 9 it is to be assumed that VFR contains the apparatus, valve amplifiers, relays and so on, necessary for receiving and responding to signals of both "X" and "Y" frequencies and that signals of "X" frequency bring about the operation of a relay having a contact *x* and that signals, received or generated, of "Y" frequency bring about the 60 operation of a relay having a contact *y*. A generator for current of "Y" frequency is connected to the third winding of transformer TR. The selector has four code marking relays connected individually to the four wires W, X, Y, Z, which extend to the register sender. It has also the usual wipers including wipers connected to wires +, -, NN, NP over which code markings are 65 transmitted for setting a second trunk selector. Contacts *h* are contacts of the switching relay, and contact *at* is a contact of a relay which is operated if a call is not to be completed locally but for which a further trunk line is required. 70 75

The wires PS, PUS, TS, SS are connected to the wires designated P, PU, T and S in Fig. 10.

When the trunk to which the incoming selector of Fig. 9 is connected is taken into use, a pulse of current at "X" frequency is received at the apparatus VFR and contact *x* closes a circuit for relay B. Relay B operates and locks up over its contact *b1* and other contacts not shown but assumed to be included in the dotted line connection between contact *b1* and earth. Contact *b2* connects earth over contacts *cos4*, *s1* and the start wire SW to bring about the association with the incoming selector of a register sender as will be described later, and contact *b3* connects battery over the non-inductive resistance in parallel with relay S and contact *ces3* to wire PS to mark the selector in the banks of the coupling switch included in the register sender circuits. Contact *b4* prepares an impulsive circuit over wire PUS, and contact *b5* connects earth to the holding windings of several relays. When a register sender becomes associated with the selector, relay S is operated over wire PS and at contact *s1* opens the circuit over the start wire SW. The impulses transmitted from a preceding exchange are received as pulses of current at "X" frequency and are repeated to the register sender at contact *x*. The impulse repeating circuit includes relay AX and wire PUS. The impulses of each train are recorded in registers as later described and the translated digits are transmitted in code form by the register sender over wires W-Z for the operation of the code marking relays. The selector is started in search of a free outlet in the marked group and when this has been found relay H operates and wires W-Z are connected over wires +, -, NN, NP, to wipers of the switch thence over the seized outlet to the second trunk selector. The code marking relays connected to wires W-Z are disconnected. As a further consequence of the operation of relay H the impulsive circuit over wire PUS is disconnected and a circuit is closed over contact *x*, relay AX contacts *b4* and *b1* for relay AY. Relay AY operates and completes the circuit of the right-hand winding of the transformer TR. The digit for the setting of the second trunk selector is transmitted by the register sender and when a free trunk has been found the register sender is released. The initiation of the release of the register sender brings about the connection of direct earth to wire SS and relay COS operates over its left-hand winding. The relay locks up over its right-hand winding and contacts *cos1* and *b5* and at contact *cos2* opens the circuit of relay RLS which is slow to operate. Contact *cos3* releases relay S, contact *cos4* opens a further point in the start wire and contacts *cos5* and *cos6* switch the trunk line through, the left- and right-hand windings of the transformer TR being completed over contacts *ax* and *ay* of relay AX and AY. As it has been assumed that the call has been extended over a further trunk, the relay having contacts *at* has been operated. Contact *at* maintains the circuit of relays AX and AY independently of contact *x* which will now be operated in response to further pulses received for the operation of registers at the succeeding exchange. Relay B is now held dependent on relay H.

On the termination of the call, release is effected by the transmission of a long pulse of "Y" frequency current and shorter successive pulses of current of each frequency whereby relay B is released. Release of relay B brings about re-

lease of relay H and all other relays in the circuit and the restoration of the selector to its normal condition.

If the incoming selector fails to find a free outlet in the marked group, whether the group be a group of trunks in a direct or alternative route it is stopped in an overflow contact position in which battery potential is applied to wire Y. A relay in the register sender is operated which connects a high resistance earth to wire SS. Relay COS does not operate owing to the high resistance of the circuit but the more sensitive relay RLS operates. Relay RLS opens a point in the circuit of the code marking relays and brings about the release of the test relay. An interval is now measured off in the register sender and the earth on wire SS is disconnected thereby releasing RLS. The selector is now ready to make a further search of a marked group of outlets when the marking shall be applied by the register sender for operating the code marking relays. This function of relay RLS is similar to that of relay RE in Fig. 2 of the drawings of British specification No. 8,378/36. If this further search is still unsuccessful the battery connected to wire Y in the overflow position brings about the application of a high resistance earth in the register sender to wire TS. Relay FB will not operate in this high resistance circuit but relay MBS is energised over its left-hand winding and operates and locks up over its right-hand windings, middle winding of relay COS and contacts *mb1* and *b5*. Other contacts of relay MBS bring about the release of the switch from the overflow position, the marking of outlets to a manual position and the starting of the selector in search of an outlet to a manual position to which the call becomes extended. The operator at the manual position now deals with the call in any way she thinks appropriate.

If the incoming selector is situated at an exchange which is in an alternative route for the call in question, relay ARS will be operated consequent on the connection to wire TS in the register sender of the positive pole of a battery the negative pole of which is earthed. The rectifier in the connection between relay ARS and fire TS prevents operation of relays ARS and FB in series. Relay ARS locks up over its right-hand winding and contacts *ars1* and *b5*. Contact *ars2* opens in the circuit for relay FC. If a state of congestion exists on the outlets from the second trunk selector from this exchange, the battery potential connected to wire Y brings about a direct earth connection in the register sender to wire TS and relay FB is operated. Relay MBS being slow to operate its armature does not become attracted before the circuit of its left-hand winding is opened at contact *fb3*. Relay FB locks up over its right-hand winding in series with the middle winding of relay COS and contacts *fb1* and *b5*. Contact *fb2* connects the source of "Y" frequency current to the third winding of transformer TR and current at "Y" frequency is transmitted back over the incoming trunk line to all preceding exchanges. At these exchanges situated in the direct route relay ARS will not be operated, and the arrival thereof of the "Y" frequency current brings about the operation of the relay in VFR controlling the contacts corresponding to *y*. This contact completes a circuit over contacts corresponding to *b6* and *ars2* for the FC relay thereat. Relay FC operates quickly and at its contact *fcl* disconnects the "Y" frequency from the incoming trunk line and

bridges the line through a suitable impedance. At contact *fc2* a circuit is closed over the middle winding of relay COS and right-hand winding of relay MBS, contacts *fc2* and *b5*. These two 5 relay sat the first exchange in the direct route encountered by the "Y" frequency current operate but the operation of relays FC at the preceding exchanges does not persist for long enough to permit operation of relays MBS there- 10 at. At the exchange in the direct route at which the alternative route was taken the call will be routed to a manual position by the operation of relay MBS thereat, the connection being switched through by relay COS.

15 If the incoming selector is situated at the trunk centre of the wanted subscriber, the digits it will receive will determine that it is to search for an outlet to a numerical selecting switch of the local automatic switch train. In this case the relay 20 controlling contact *at* will not be operated so that relay AY will respond to impulses received at VFR and repeated by contact *x*. Contact *ay* will repeat loop impulses to the impulse receiving relays of the several numerical selectors concerned, it 25 being understood that relay COS will have been operated as soon as the last digit for the setting of the incoming selector has been transmitted.

When the incoming selector is taken into use and relay B is operated a signal is transmitted to 30 a register sender to cause it to associate itself with the selector. The circuits of a suitable register sender are shown in Figs. 10 and 11, the wires PS, PUS, TS, SS outgoing from the bottom of Fig. 9 corresponding to the wires P, PU, T, S 35 incoming on the left of Fig. 10, wires W, X, Y, Z being similarly designated in both figures. As is the case with the register sender shown in Figs. 1 to 8, the register sender of Figs. 10 and 11 is one of a number connected to a chain circuit. 40 The wire IN corresponding to wire SW of Fig. 9. Association of the register sender with the incoming selector is effected by the motor driven coupling switch SC the motor of which is represented by the latch magnet SCM. In the sender 45 of Figs. 10 and 11 the impulses for determining the translation to be effected are received over wire PU on relay A and repeated by this relay to stepping switches 1C and 2C. Code marking relays AW—AZ effect the marking of the signalling wires W—Z for the transmission of the coded 50 digits. The stepping switches are under the control of a sequence switch SQ which directs the impulse trains to the stepping switches in turn and connects up the signalling wires to the marking 55 battery for the transmission of successive coded digits. The translating switch is a motor driven switch with 16 wipers CM1—CM16, the motor mechanism being represented by its latch magnet CMU.

60 There is also a sending switch SW for the transmission of impulses in the case in which an alternative route is taken. The impulses are generated by relay Y as is the case in the originating exchange register sender and their transmission 65 is under the control of relays SS and SZ. As in the register sender of Figs. 1 to 8 relays PY and SY are relays controlling the translation, Co is the cut-off relay and RL the relay which brings about the measurement of an interval after an 70 unsuccessful search by the incoming selector. Relays MB and FB concern the routing of a call to a manual board position at the same exchange or a preceding exchange and relay AR is operative only when the sender is situated at an exchange 75 included in an alternative route.

The operation of the circuits shown in Figs. 10 and 11 will now be described in detail the assumption first being made that the register sender is situated in an exchange B in a direct trunk route and that as a result of the impulse trains received 5 a further direct trunk in the required direction is connected up. After this will be considered the operations which ensue when the register sender is situated in an indirect route and when a trunk in an indirect route is connected up consequent 10 on the coded digits transmitted by the apparatus in question.

Relay C is normally operated and when the register sender is taken into use relay ST is operated over wire IN and wire SW in Fig. 9 and 15 the hunting switch searches for the incoming selector requiring the register sender. The circuit operations effecting this action are similar to those described in connection with Figs. 1 to 8 and need no further description here. When the 20 incoming selector is found, relay TC operates to stop the switch and remove a short-circuit from relay B which operates in series with magnet SCM and locks up over contact *b4*. Contact *b1* connects impulse receiving relay A over wiper 25 7 to the pulse wire PU, contact *b2* connects the left-hand winding of relay ZS to an earth pulse wire, contact *b3* disconnects relay SH and connects a holding circuit for many of the relays, contact *b5* prepares a holding circuit for relay 30 CO and contact *b6* releases relay C and lights the pilot lamp PL. Relay C on releasing extends the chain start wire to the next register sender in the chain. Relay A operates over the pulse wire in series with relay AX in the incoming selector 35 and at contact *a1* closes a circuit over contact *b3* for relay BA. Relay BA operates and locks up over contact *ba1*. Relay ZS having operated, contact *ba1* closes a holding circuit for this relay over contacts *zs1* and also closes the following 40 circuit, earth over contacts *ba7*, *ri7*, wiper *SQ6*, magnet *SQM*, left-hand winding of relay RB to battery. The magnet and relay RB operate and by the opening of contact *sgm* the magnet releases itself and the sequence switch is stepped to 45 position 1. Relays RA and RB operate with the effects described earlier. Contact *ba3* prepares circuits for stepping switch magnet *1CM* and operating relay CC, contact *ba4* opens the homing circuit for the register stepping switches, contact *ba5* opens the homing circuit for the sequence 50 switch and contacts *ba2*, *ba6* and *ba3* are without effect at the present stage of operation.

The first impulse train is now received. If the 55 train consists of one impulse it denotes a call to be completed within the exchange area. On the release of relay A contact *a1* closes circuits for magnet *1CM* and relay CC. The relay operates and at contact *cc1* closes a circuit over wiper *SQ6* in position 1 for magnet *SQM*, and at contact *cc2* 60 opens a point in the circuit of winding (I) of relay CT. At the end of the impulse, relay A re-operates and magnet *1CM* releases stepping the register switch to position 1. After a short interval relay CC releases and connects winding (I) 65 of relay CT to contact 1 in the bank of wiper *1C2*. Relay CT operates in a circuit over this wiper and contact *b3* and connects relays AW—AZ to wipers *CM5*—*CM8* but without effect since the translating switch is in its normal position. Con- 70 sequent on the opening of contact *cc1* the sequence switch is stepped to position 2. A circuit is now closed over wiper *SQ6*, back contact *ar2* and contact *sgm* for magnet *SQM* and the sequence switch self-steps to position 3. Contact 75

ct6 opens a point in the circuit of magnet CMU and contact ct7 connects battery over relays TS and TT to contacts 3 in the banks of wipers SQ1 and SQ2 to mark wires W and X to operate code relays in the incoming selector for the setting of this selector to outlets to a local numerical selector. Relays TS and TT operate in series with the code marking relays in the incoming selector. When the setting of the incoming selector has been completed, relay TS releases followed by relay TT. During the release period of relay TT relay DS is operated over contacts tt2 and ts1. Contact ds2 connects the right-hand winding of relay MB to contact 3 in the bank of wiper SQ3 so that if no free link has been found battery potential applied over wire Y at the distant selector or a relay set in the link outgoing from the incoming selector operates relay MB. The relay locks up over contact mb1 and at contact mb2 connects a high resistance earth over contact ba2 to wire T to operate relay MBS in the incoming selector to route the call to a manual board position.

If the first digit received at the incoming exchange is other than 1, relay CT will not be operated and no circuit will be closed over relays TS and TT and wires W and X. At the end of the digit relay CC will release and the switch SQ will be stepped to position 3 as before. If the first digit be any of the numbers 6-0, a self-drive circuit will be closed immediately for switch 2C the circuit extending over wiper 2C2 and commoned contacts 0-9 and commoned contacts 6-10 in the bank of wiper 1C2 and switch 2C will step rapidly to position 10 from which position stepping in response to the second digit will take place. If the first digit be one of the numbers 2-5, this self-driving circuit for switch 2C will not be closed and stepping in response to the second digit will take place from contact 0. This enables only five wipers of switch 2C to be connected in the test circuit for an alternative route translation and permits two translations to be made for the same position of wiper 1C4, one for first digits of 2-5 and another for first digits of 6-10 impulses. Later positions in the banks of switch 1C are used for a like purpose when the register sender is taken into use for a call in which the exchange at which it is situated is in an alternative route. This use of switch 1C will be explained later. The second digit is received by relay A and is repeated to magnet 2CM and switch 2C is stepped in accordance with the impulses received and relay CC is re-operated.

At the end of the impulse train, relay CC releases and magnet SQM which was operated over contact ct1 and wiper SQ6 in position 3 releases and the sequence switch is stepped to position 4. In this position magnet CMU is operated consequent on the closure of a circuit from earth over contacts ba1, r11, wiper SQ8, contacts ta1, ct5, ba6, the winding of the translating switch latch magnet CMU, relay RA to battery. The magnet operates and starts the motor. The translating switch rotates until a circuit for relay TA is found over contact sy4, wiper CM15, bank contacts and wipers 2C3 and 1C3 and bank contact and wiper CM14.

When such a circuit is found, relay TA operates and by opening its back contact ta1 de-energises magnet CMU and by closing its front contact ta1 operates relay GC. Contacts gc1-gc4 prepare circuits for relays AW-AZ over wiper CM1-CM4 for determining the code marking to be applied for the transmission of the first digit

for setting trunk selectors in the exchange and contacts gc5-gc7 close in group control circuits. In particular, contact gc5 prepares a circuit for the left-hand winding of relay MB which is closed if earth is present on wire CDL denoting that delay working is in force. Contact gc6 closes in a circuit for the right-hand winding of relay SY which is closed if earth is present on wire CSY denoting that there are alternative trunks free and available to the direct trunk route selected in accordance with the received digits and contact gc7 closes a similar circuit for relay PY if there are direct trunks free in the desired route, earth being applied in this instance to wire CPY. Relay S operates by means of its winding (I) in parallel with relay GC. Contact s1 completes a locking circuit for relay S over its winding (II) and contact b3, and contact s2 opens in the circuit which might be closed over wire CDL and closes a point in a further circuit for relay MB.

It will first be assumed that a direct trunk to the next exchange D, along the desired route is available and in consequence relay PY is operated over wire CPY. The relay locks up over its left-hand winding and contact py1 disconnects the operating circuit for the slower operating relay SY at contact py2 and the circuit for relay MB at contact py3. As relay S is slow in operating, this circuit is opened before contact s2 has changed over. Contact py5 closes a circuit for winding (II) of relay CT over contact sy5 and contact py6 closes a point in a circuit for winding (I) of relay RL. Relay CT operates and connects one or a pair of the relays AW-AZ over wipers CM1-CM4 to earthed wires the relays operated depending on whether the wires are connected to the particular bank contacts on which wipers CM1-CM4 are resting or not. Consequent on the closure of contact ct7, relays TS and TT are connected over one or more of the wipers SQ1-SQ4 to wires W-Z for the operation of the code marking relays in the incoming selector. The incoming selector hunts for a free outlet in the marked group and when it has found one giving access to a second selector and has switched the connection through, relays TS and TT release in succession and during the release period of relay TT relay DS is operated. On the closure of contact ds1 magnet SQM is operated in a self-stepping circuit and the sequence switch is stepped to position 5. When relay DS releases, a further self-stepping circuit for the sequence switch magnet is closed over wiper SQ6 in position 5 and back contact ds1 and the switch is stepped to position 6. When the switch left position 4 relay GC was released at wiper SQ8 and contacts gc1-gc4 release relays AW-AZ and connect them over wipers CM5-CM8 to be operated in accordance with the second digit to be transmitted. This digit is transmitted in position 6 of switch SQ and after the second selector code marking relays have been released the sequence switch is advanced to position 8. In this position a third digit is transmitted to cause the second selector to search and to indicate to it whether the group of trunks to be searched is included in a direct or indirect route. As regards the transmission of the third digit, this is effected by the operation of relays AW and AX if search is to be carried out in a group of direct trunks and by the operation of relays AW, AX and AY if an alternative route is concerned.

After the transmission of the third digit the sequence switch moves to position 10 in which a circuit for winding (I) of relay CO is completed

over wiper SQ6 and release of the register sender takes place. Relay CO locks up over contacts *co1* and *b5* and at contact *co2* applies a direct earth over wiper 5 to operate relay COS in the incoming selector. As a result of relay COS operating, the circuit over wire P is opened and relay TC is released. Contact *tc1* short-circuits relay B bringing about its release. The general holding circuit is opened at contact *b3* and relay BA releases. A homing circuit for switch SQ is closed over wiper SQ7 and contact *ba5* and relay RB energising in series with magnet SQM holds relay CO over contacts *co1* and *rb3* until the switch reaches its normal position. A homing circuit is 10 also closed over contact *ba4* and wiper *!C1* for switch *!C* and when this reaches its normal position wiper *!C1* extends the homing circuit over wiper *2C1* for the purpose of homing switch *2C*. The translating switch is homed consequent on 15 the closure of back contact *ba6* and magnet CMU remains energised until the switch reaches its normal position in which contacts *cmon1* open to bring it to rest. Relay RB remains operated until all the switches are at normal thereby maintaining relay CO operated to guard the register sender.

If on receipt of the first digit the incoming selector is unable to find a free link to a second selector, it rotates to a last contact position and 20 the circuit of relays TS and TT is opened. Switch SQ is stepped to position 5 and while in this position battery connected to wire Y operates relay RL over wiper SQ3, contacts *rm3*, *ct6*, *py6* and winding (I) of relay RL. The relay locks up over 25 its winding (II), contact *rl8* and wiper SQ7. Contacts *rl1*—*rl4* open the signalling wires to the incoming selector, contact *rl5* connects high resistance earth to wire S to operate relay RLS in the incoming selector, contact *rl6* provides a 30 holding circuit for relay RL in the normal position of the sequence switch and contact *rl7* closes a circuit for relay RM over its right-hand winding. Relay RM locks up over its left-hand winding and contact *rm1*, at contact *rm2* extends earth to relay Y and at contact *rm3* disconnects winding (I) of relay RL and connects 35 relay MB to the fifth contact position in the bank of wiper SQ3. Relay Y generates impulses by means of its contact *y2* in the manner described 40 for relay Y in Fig. 5, each operation of this contact transmitting an impulse at a speed of from 10 to 14 impulses per second to magnet SQM. Switch SQ is stepped until wiper SQ7 steps off the 24th contact. At this time, a wiper 45 diametrically opposite to the wiper SQ7 shown is stepped to the normal contact of the switch and relay RL is held over this contact and contacts *rl6* and *co5*. Stepping continues until position 4 is reached whereupon the holding circuit for 50 relay RL is opened and the relay releases and opens the pulsing circuit for relay Y. In position 4 relay GC re-operates and the first coded digit is again transmitted. If congestion is still encountered, renewed application of battery to 55 wire Y when the sequence switch is in position 5 brings about operation of relay MB and the routing of the call to a manual board position. If the second trunk selector fails to find a free trunk due to the last available one being taken during 60 the search by the first and second trunk selectors, battery is applied to wire Y which in position 9 of switch SQ operates relay MB and the call is routed to a manual board position by the incoming selector. If at the time of setting switch CM 65 there were no direct trunks to exchange D free,

earth would be absent from wire CPY but if an alternative route trunk is available and free earth will be present on wire CSY and relay PY not being operated relay SY operates. Contacts *sy1*, *sy2*, *sy3* and *sy6* perform similar function to the 5 similarly designated contacts of relay PY, contact *sy4* releases relay TA and connects it over contact *py4* to wiper *!C4*, contact *sy5* opens to prevent operation of relay CT at this time and contact *sy7* prepares a circuit for relay Y and disconnects relay CO from contact *!0* in the bank of wiper SQ6. Due to contact *ta1* falling back the circuit for magnet CMU is closed and the translation switch commences to rotate in search of a marking denoting an alternative route 10 to the direct trunk route indicated by the received digits. Such a route may reach exchange D via exchange E. This marking is made to the bank of wiper CM16 over wipers of the stepping switches *!C* and *2C* and when wiper CM16 encounters such a marking, relay TA is operated over wiper *!C4* and the appropriate one of the wipers *2C4*—*2C8*, bank and wiper CM16 to battery. The translating switch is stopped and relays CC and S are operated. Relay CT operates 15 by means of its winding (II) over contact *py5* in parallel with a non-inductive resistance and in series with relay TA and the code relays for the first code digit are operated. This digit and the second and third code digits are transmitted as 20 previously described and a trunk to exchange E is selected. Switch SQ is stepped to position 19 whereupon a circuit is closed over wiper SQ6 and contact *sy7* for relay Y which is thereby started pulsing. The first pulse is transmitted to 25 magnet SQM to step the switch to position 11 and four subsequent pulses step it to position 15. In position 11 the right-hand winding of relay PY is operated over contact *sy2* and wiper SQ8, contact *py4* disconnects relay TA which releases 30 and the translation switch drives until the route marking is found, the circuit for relay TA being over contacts *sy1*, *py4*, wipers CM15, *2C2*, *!C3* and wiper CM14. This takes place due to the high speed of operation of the translation switch 35 while the sequence switch steps from position 11 to position 15. In position 15 of the sequence switch a circuit is completed over wiper SQ8 for winding (I) of relay SS and for marking contact 40 11 in the bank of wiper SW2. Contacts 1 to 10 in this bank are connected to wipers SM12 and CM13 in such a way as to provide for the transmission of two digits for setting switches in exchange E for the selection of a further trunk to 45 reach exchange D, the impulses to be transmitted being determined by the direct trunk route translation effected by the translation switch. The connection to contact 11 is provided for the transmission of 11 impulses to denote at exchange 50 E the fact that the call is one in which the exchange will be concerned in an alternative route. 55 When relay SS has operated it locks up over its winding (II) and contact *ss1*. Contact *ss2* disconnects wiper SQ1 from wire W and connects this wire to wire X over contact *y1*, contact *ss3* closes a circuit over wiper SQ6 and contacts *ar5* and *sy8* for relay Y which commences pulsing, and contacts *ss4* and *ss5* connect the pulsing circuit to magnet SWM. At each operation of relay Y magnet SWM is energized the 60 circuit being from earth over wiper SQ9, contacts *ss3*, *ar5*, *sy8*, *sz3*, *y2*, *ss4*, *sz4* and *ss5*. Magnet SWM steps the sending switch at each pulse until the eleventh contact in the bank of wiper SW2 marked by earth over wiper SQ8 is encoun- 65 70 75

tered wherupon relay SZ operates in the above traced marking circuit. At each pulse delivered by relay Y contact *y1* opens the loop over wires W and X to transmit an impulse to impulse receiving apparatus in the distant exchange. Operation of relay SZ short circuits contact *y1* at contact *s21*, closes a locking circuit for itself over wiper SW1 at contact *s22*, closes an operating circuit for magnet SQM and opens the circuit for relay Y at contact *s23* and closes a homing circuit for the sending switch at contact *s24*. Magnet SWM operates in a self-stepping circuit over contacts *ss5*, *s24*, *swm* and wiper SW1 and homes the sending switch. Relay SZ releases in the home position of the sending switch and re-closes the circuit of relay Y. Magnet SQM releases and switch SQ steps to position 16 in which the marking circuit for the determination of the second impulse train is extended to the bank of wiper SW2 over wipers SW8 and CM13. The second impulse train is transmitted and switch SW is again homed and the sequence switch stepped to position 17. In this position the marking circuit for the determination of the third impulse train is extended to the bank of wiper SW2 over wipers SQ8 and CM12 and the third train is transmitted after which the sequence switch is stepped to position 18. The circuit for relay Y in positions 16 and 17 of the sequence switch does not include contacts *ss3*, *ar5*, *sy8*. In position 18 relay CO is operated and the register sender is released.

If there are no alternative routes free, neither relay PY nor relay SY will be operated and relay MB is operated by means of its left-hand winding in a circuit over contacts *ar4*, *zz1*, *py3*, *sy3* and *s2* to earth. If delay working on the particular trunk route is in force, relay MB will be operated before relay S operates by the extension of earth over wire CDL, wiper CM9 and back contact *s2*.

The case in which the arrangements shown in Figs. 10 and 11 are situated at an exchange in an alternative route, for example, the exchange E, will now be considered. It will be remembered that on the operation of relay SY, a preliminary train of 11 impulses was transmitted followed by two route selecting trains. At exchange E, a register sender having been taken into use and connected to the incoming selector, relay A is connected to wire PU and the sequence switch is stepped to position 1. Relay A now receives a train of 11 impulses which it repeats to switch 1C. This switch is accordingly set to its eleventh contact position in which a circuit is closed from earth over contact *b3*, wiper 1C2, relay AR to battery. Relay AR operates and locks up over contact *ar1* and at contact *ar2* opens the self-stepping circuit for magnet SQM in position 2 of the sequence switch and prepares a steady energising circuit for that magnet. Contact *ar3* substitutes relay FB for relay MB to receive a signal that congestion has been encountered by a trunk selector, contact *ar4* makes a similar substitution to receive a forced release signal, and contact *ar5* prepares a pulsing circuit for relay Y to generate the impulses requisite for setting the switches in the distant exchange, in the example, exchange D, and contact *ar6* applies a high resistance positive battery connected to wire T to operate relay ARS in the incoming selector. At the end of the train of 11 impulses the sequence switch steps to position 2 in which a steady energising circuit is prepared for magnet SQM. The first impulse train for determining the translation to be effected is now received

on relay A and repeated to switch 1C in position 2 of the sequence switch and relay CC is operated. Magnet SQM is energised and remains energised throughout the impulse train. If the train comprises more than 5 impulses, switch 2C is automatically stepped to position 10 as before but if less than 6 impulses are received this self-stepping of switch 2C does not take place. At the end of the impulse train relay CC releases and opens the circuit of magnet SQM and the sequence switch is stepped to position 3 to connect the impulse repeating circuit to magnet 2CM. Switch 2C is set by the third train of impulses and switch SQ moves to position 4 and translation takes place. If free trunks are available, the first and second trunk selectors are set in the same manner as that described for exchange B, provision being made for a re-search by the first trunk selector. If congestion is still encountered by this selector after a second search, battery on wire Y is extended over wiper SQ3 in position 5 and front contacts *rm3* and *ar3* to the right-hand winding of relay FB. Relay FB operates and locks up over its left-hand winding and contact *fb1* and at contact *fb2* connects direct earth over wiper 6 to wire Y to cause the incoming selector to transmit a signal indicative of a congested condition to the preceding exchange in the direct route, i. e., exchange B, to cause the manual board operator thereat to be signalled.

A similar operation occurs if the second trunk selector fails to find a free trunk, relay FB being operated in this instance over wiper SQ3 in position 9.

Relays ZS and ZZ operate in the same manner as the correspondingly designated relays in Fig. 7, contact *zz1* connecting earth over contacts *b3* and *ar4* to relay MB or FB as the case may be, the result being that the call is routed to a manual board position at the same exchange or at a preceding exchange.

I claim:

1. In a telephone network, a plurality of exchanges, automatic switches in each exchange, each of said register sending means at each exchange, each of said register sending means responsive in turn, during the progressive establishment of an inter-exchange connection through said exchanges, to digits designating the next of said exchanges to be included in the connection, each of said register sending means having associated therewith translating means then effective to select a route for the extension of the connection to said next exchange and to translate the received digits in accordance with the selected route, said register sender then effective to transmit the translated digits to control the extension of the connection over said switches.

2. A network as claimed in claim 1 in which, when any of said register sending means, routes the connection from the exchange in which said register sending and translating means is located to the next of said exchanges through an intermediate exchange not designated by the digits received by said register sending means, said translating means is also effective to cause said register sending means to automatically generate and transmit digits to set the switches at said intermediate exchange.

3. In a telephone exchange wherein automatic switches have access to outgoing trunk lines of different classes, register sending means, means for marking said register sending means, translating means associated with said register send-

ing means effective responsive to the receipt of said marking to make simultaneously a primary translation and a secondary translation of said marking, means effective responsive to the completion of said translations for determining, before either of the translations is rendered effective, if said primary translation shall be effective to control one of said switches to search immediately for an idle trunk in one of said classes, or, 5 alternatively, if said secondary translation shall be effective to control one of said switches to search immediately for an idle trunk in another one of said classes.

4. In a telephone exchange wherein automatic switches have access to outgoing trunk lines of different classes, register sending means, means for marking said register sending means, translating means associated with said register sending means effective responsive to the receipt of 10 said marking to make simultaneously a primary translation and a secondary translation of said marking, means effective only after the completion of said translations for determining in which, if either, class of trunk lines designated by said 15 translations there is an idle trunk line, and means controlled conjointly by said last two means for then operating one of said switches to search for an idle trunk line in said class designated by said primary translation if, according 20 to said determination, there is an idle trunk line in that class.

5. In a telephone exchange wherein automatic switches have access to outgoing trunk lines of different classes, register sending means, means for marking said register sending means, translating means associated with said register sending means effective responsive to the receipt of 25 said marking to make simultaneously a primary translation and a secondary translation of said marking, means effective only after the completion of said translations for determining in which, if either, class of trunk lines designated by said 30 translations there is an idle trunk line, and means controlled conjointly by said last two means for then operating one of said switches to search for an idle trunk line in the class designated by said secondary translation if, according 35 to said determination, there is no idle line in the class designated by said primary translation but there is an idle trunk line in the class designated by said secondary translation.

6. In a telephone exchange wherein automatic switches have access to outgoing trunk lines of different classes, register sending means, means for marking said register sending means, translating means associated with said register sending means effective responsive to the receipt of said marking to make simultaneously a primary translation and a secondary translation of said marking, means effective only after the completion of said translations for determining in which, if either, class of trunk lines designated by said 40 translations there is an idle trunk line, and means controlled conjointly by said last two means for then operating one of said switches to search for an idle trunk line in the class designated by said primary translation if, according 45 to said determination, there is no idle trunk line in either class.

7. In a telephone exchange having direct trunk lines to another exchange and alternative trunk lines for establishing an indirect connection to said other exchange, and wherein automatic switches have access to said trunk lines, register sending means, means for marking said register

sending means, means associated with said register sending means effective to translate said marking into one marking for operating one of said switches to search for an idle direct trunk line and simultaneously into another marking for operating one of said switches to search for an idle alternative trunk line, means effective responsive to the completion of said translation and before the operation of said switches for determining the condition of said trunk lines, last said means effective to render said one marking only effective if there is an idle direct trunk line and to render said other marking only effective if all direct trunk lines are busy and there is an idle alternative trunk line.

8. In a telephone exchange having direct trunk lines outgoing to another exchange and alternative trunk lines for setting up an indirect connection to said other exchange, automatic switches having access to said trunk lines, said switches controllable by register sending and translating means associated with an operator's position in said exchange, said switches controllable also by other register sending and translating means associated with incoming trunk lines, means for marking either register sending and translating means, either of said translating means when marked effective to make simultaneously a primary translation of said marking to control one of said switches to search for an idle direct trunk line, and a secondary translation of said marking to control one of said switches to search for an idle alternative trunk line, means effective upon the completion of said translations for determining which of said translations shall be effective.

9. In a telephone exchange such as that claimed in claim 8, means effective when a call is originated by marking the register sending and translating means associated with said operator's position for storing said call if one of said switches searches in accordance with a primary translation of said marking that fails to find an idle direct trunk line.

10. In a telephone exchange such as that claimed in claim 8, a manual position, means effective when a connection is extended through said exchange by marking said register sending and translating means associated with one of said incoming trunk lines for extending said connection to said manual position if one of said switches searches in accordance with a primary translation of said marking and fails to find an idle direct trunk line.

11. In a telephone system such as that claimed in claim 8, means effective when a call is originated by marking the register sending and translating means associated with said operator's position for storing said call if all of said direct trunk lines are busy and one of said switches searches in accordance with a secondary translation of said marking and fails to find an idle alternative trunk line.

12. In a telephone system such as that claimed in claim 8, a manual position, means effective when a connection is extended through said exchange by marking said register sending and translating means associated with one of said incoming trunk lines for extending said connection to said manual position if all of said direct trunk lines are busy and one switch searches in accordance with a secondary translation of said marking and fails to find an idle alternative trunk line.

13. In a telephone exchange such as that

claimed in claim 8, means effective when no direct trunk line is idle to render said primary translation of said marking effective if one of said switches searches in accordance with said secondary translation of said marking and fails to find an idle alternative trunk line.

14. In a telephone network, a first exchange in which outgoing selectors have access both to trunk lines to a second exchange and to trunk lines to a 10 third exchange, trunk lines extending between said second exchange and said third exchange, register sending means in said first exchange for operating said outgoing selectors, means for marking said register sending means to extend a 15 connection from said first exchange to said second exchange, means associated with said register sending means for translating said marking into a primary marking to designate said trunk lines to said second exchange and into a secondary 20 marking to designate said trunk lines to said third exchange, means effective responsive to the completion of said translations and before any outgoing selector is operated by said register sending means for determining the condition of 25 said designated trunk lines, said last means effective if there is no idle trunk line to said second exchange and there is an idle trunk line to said third exchange to render said translating means effective in accordance with said secondary marking to control one of said outgoing selectors to seize an idle trunk line to said third exchange and to automatically transmit thereover impulses to control switches at said third exchange to seize an idle trunk line to said second exchange.

35 15. In a network such as that claimed in claim 14, in which said last means is effective if there is an idle trunk line to said second exchange to render said translating means effective in accordance only with said primary marking to control one of said outgoing selectors to seize an idle trunk line to said second exchange.

16. In a telephone network, a plurality of exchanges, means including trunk lines between said exchanges for involving said exchanges serially in a connection, means in one said exchange effective only when no trunk lines to the succeeding exchange in said serial connection are idle to automatically reroute said connection, last said means including trunk lines to an alternative exchange, trunk lines from the alternative exchange to said succeeding exchange, and means for automatically seizing one of said trunk lines to said alternative exchange and for automatically generating and transmitting thereover impulses to cause switches at said alternative exchange to seize one of said trunk lines from said alternative exchange to said succeeding exchange, a manual position in said one exchange, means effective if no trunk line from said alternative exchange to said succeeding exchange is idle for automatically extending said call to said manual position.

17. In a device for controlling automatic switches to extend connections to outgoing lines, 65 said outgoing lines being arranged in groups, register sending means for operating said switches, means for marking said register sending means, means associated with said register sending means for translating said marking into 70 a plurality of secondary markings each designating a group of outgoing lines, means for determining the condition of the outgoing lines designated by each secondary marking responsive to the completion of the translation of said last 75 means and for then rendering only one of said

secondary markings effective to control the switches to extend a connection in accordance with said determination.

18. In a register controller for use in a telephone system to transmit digits responsive to the receipt of an exchange code, registering means for receiving a code characterizing any exchange to which it is desired to extend a call, means operated by said last means responsive to the receipt of said code to determine simultaneously in which of a plurality of routes to the desired exchange an idle trunk is to be found, and means for transmitting routing digits in accordance with said determination.

19. In a register controller for use in a telephone system to set up connections over alternative trunk groups, registering means set in response to incoming impulses, means controlled responsive to and in accordance with the setting of said registering means for determining simultaneously in which, if any, of a plurality of groups of trunks there is an idle trunk, and means for then transmitting impulses in dependence upon said determination for setting up a connection over a trunk in a particular one of said plurality of groups of trunks.

20. In a telephone system, direct trunks between a first exchange and a second exchange, indirect trunks including a tandem exchange between the first exchange and the second exchange, 30 switches at the first exchange having access to said trunks, a register controller in the first exchange, means for transmitting to said controller digits characterizing the second exchange, and means in said controller responsive to the receipt of said digits for determining the condition of said direct and indirect trunks to the second exchange and for then causing said controller initially to transmit routing digits to control the extension of a connection over said switches and 40 said indirect trunks if no direct trunks are free.

21. In an automatic telephone system wherein a first exchange, a second exchange and a third exchange are connected in series in the order named by trunk lines, and wherein the extension of calls from the first exchange to the third exchange through the second exchange is controlled conjointly by a code characterizing the second exchange and a code characterizing the third exchange, means at the first exchange for translating only the code characterizing said second exchange and controlling the switches at said first exchange in accordance with said translation of the code to extend the call to said second exchange, and means at the second exchange for translating only the code characterizing said third exchange and controlling the switches at said second exchange in accordance with said last translation to extend the call to said third exchange.

22. In an automatic telephone system wherein calls from an originating exchange to a terminating exchange are extended progressively through one or more tandem exchanges under control of a code sending device at the originating exchange, 65 a register at each exchange effective when the connection has been established to that exchange to register that part of the code originated by said sending device which identifies the next exchange to which the connection is to be extended, 70 and means at each exchange for translating only said part of the code registered by the register at that exchange and controlling the extension of the connection to the next exchange in accordance with the translation thereof.

23. In an automatic telephone system as claimed in claim 22, wherein the connection from certain of the exchanges to the corresponding next exchange identified by the code may be 5 extended over any of plurality of routes, and wherein the translating means at each of said certain exchanges makes a plurality of translations each corresponding to one of said routes, means for determining in which, if any, of said 10 routes there is an idle trunk line outgoing from the certain exchange and then, in dependence upon said determination, rendering a particular one of said translations effective to control the extension of the connection to the next exchange 15 over the route corresponding to that translation.
24. In an automatic telephone system wherein a connection may be extended from a first exchange to any of a plurality of other exchanges through a tandem exchange having trunk lines 20 to each of said plurality of exchanges, and wherein, during the extension of such a connection, after same has been completed from said first exchange to said tandem exchange, a code characterizing the desired one of said plurality of exchanges 25 is transmitted to said tandem exchange over the trunk line from said first exchange, a translator at said tandem exchange associated with the incoming end of the trunk line from said first exchange for receiving and translating 30 said code and then controlling the switches at said tandem exchange in accordance with the translation of said code to extend the connection to said desired one of said plurality of exchanges.
25. In an automatic telephone system wherein 35 a connection may be extended from a first exchange to a second exchange through a tandem exchange, wherein, during the extension of such a connection, after same has been completed to said tandem exchange a code characterizing said 40 second exchange is transmitted to said tandem exchange over the partly established connection,

and wherein said connection may be completed from said tandem exchange to said second exchange over either a direct or an indirect path, a translator at the tandem exchange operated by said code to prepare two secondary codes differing from one another but each having a predetermined relationship to the code characterizing said second exchange, and means for at times transmitting one of said secondary codes to control the completion of said connection to the second exchange over said direct path. 10

26. In an automatic telephone system wherein a connection may be extended from a first exchange to any of a plurality of other exchanges via a tandem exchange having one or more direct trunk lines to each of said plurality of exchanges, 20 and wherein, during the extension of such a connection, after same has been completed to said tandem exchange a code characterizing the desired one of said plurality of exchanges is transmitted to said tandem exchange over the partially 25 established connection, a translator at the tandem exchange operated by said code and normally effective to control the switches at said tandem exchange in accordance with a particular translation of said code to seize a direct trunk line to 30 the desired exchange, and means effective if no direct trunk line to the desired exchange is available for preventing said translator from operating the switches at said tandem exchange in accordance with said particular translation and causing 35 said translator to control said switches in accord with a different translation of said code to seize a direct trunk to a different one of said plurality of exchanges. 40

BERNARD ANTHONY HENSLER.
